UNITED STATES PATENT OFFICE.

MYRON COSSEY, OF NEW YORK, N. Y., ASSIGNOR TO RELIANCE BALL BEARING DOOR HANGER COMPANY, OF NEW YORK, N. Y., A CORPORATION OF NEW YORK.

GRAVITY DOOR-LOCK.

1,130,150.

Specification of Letters Patent. Patented Mar. 2, 1915.

Application filed July 15, 1914. Serial No. 851,060.

To all whom it may concern:

Be it known that I, MYRON COSSEY, a citizen of the United States, residing in the borough of Brooklyn of the city of New York, in the State of New York, have invented certain new and useful Improvements in Gravity Door-Locks, of which the following is a specification, reference being had to the accompanying drawings, forming a part hereof.

This invention relates to locks for doors adapted to be operated by gravity and is concerned particularly with the use of such locks in connection with sliding doors, such as are commonly employed in connection with elevators.

The invention has for its principal object to provide a lock in which the operating parts are so disposed as to insure a strong pull thereon by gravity to lock the door while permitting easy manipulation thereof by the operator for the unlocking of the door.

A further object is to provide a lock of the character indicated which shall have one portion of its actuating mechanism arranged to be grasped by the operator to initiate movement of the lock and simultaneously to move the door.

Another object is to avoid the use of springs which have proved inefficient and liable to frequent breakage.

Still another object is to simplify the construction of gravity locks, thereby lessening their cost of manufacture and rendering them less liable to derangement than known types of locks.

The invention will be described more particularly with reference to the accompanying drawing, in which the figure is a fragmentary view in front elevation of a gravity lock embodying the present invention and showing its application to a sliding elevator door.

In the figure the improved lock is shown as applied to a sliding door *a*, suspended from a movable carrier *b* mounted on fixed tracks *c* as by balls *d*. The door *a* is shown in its closed position with its inner edge abutting against the proximate edge of the frame *e* of what may be the wall of the elevator well. On the carrier *b* is pivotally mounted as on a bracket *b'*, a rocking lever *f* having a nose *f'* constituting a latch which is adapted to engage with a fixed

abutment *c'* which may be mounted conveniently on one of the fixed tracks *c*. To the opposite end of the latch *f* is secured pivotally an operating link *g*, which may be disposed in a substantially vertical position and extend downward in juxtaposition to the inner face of the door *a*, and have secured pivotally to its lower end a bell crank lever *h*, one arm of which, as *h'*, may be formed to constitute a handle for engagement by the hand of the operator. The bell crank lever *h* is supported on a pivot pin *i* carried by the door *a* or a suitable plate *i'* fixed to the face of the door. It will be noted that the point of pivotal attachment of the lower end of the link *g* to the bell crank lever *h* is off center with respect to the pivot pin *i* by which the lever is supported, so that the weight of the link *g* together with the tail of the latch *f* serves to hold the nose *f'* of the latch in a relatively raised position for engagement with the fixed abutment *c'* on the track *c*. When the operator desires to open the door he grasps the depending arm *h'* of the bell crank lever *h* so as to rock the lever about the pin *i* and raise the link *g* vertically so as to depress the nose *f'* of the latch *f* and disengage it from the fixed abutment *c'*. Movement of the bell crank lever *h* about the pin *i* in this manner, may be limited by a suitable buffer *k* carried by the plate *i'* and preferably provided with resilient cushions *k'* and *k''* with which engage respectively the handle *h'* and the lower end of the link *g*. Engagement of the grip *h'* with the buffer *k'* will limit the rocking movement of the lever *h* about the pin *i*, and continued pressure on the grip will serve to slide the door to opened position. Conversely, when the grip *h'* is released by the operator the cushion *k''* will serve to limit the downward movement of the link *g* and prevent noise. If desired, a second plate *i''* may be secured on the outer side of the lever *h* and the buffer *k* so as to inclose portions of these parts and protect them.

It is to be understood that the lever *h* will be mounted on the inner face of the door at such a height as to place the operating grip *h'* in convenient reach of the operator to facilitate the opening of the door.

The embodiment illustrated represents the preferred forms of the present invention since this embodiment has the advantages of

simplicity in construction, cheapness in manufacture and facility in application of the lock to the door, but it is to be understood that the invention may assume other forms by changes in construction of the elements and rearrangements of the parts, but all such changes and rearrangements are to be deemed within the scope of the invention provided they fall within the terms of the appended claim.

10 I claim as my invention:

15 In combination with a sliding door and carrier therefor, a gravity lock including a latch mounted pivotally on the carrier, a fixed abutment with which the nose of the latch engages, a link pivotally secured to the tail of the latch and extending downwardly in a substantially vertical plane in juxtaposition to the inner face of the door, a bell 20 crank lever mounted pivotally on the door within convenient reach of the operator and having one end of one of its arms pivotally

attached to the lower end of the link and having the other arm formed to constitute a grip, the weight of the link and the first 25 named arm of the bell crank lever being unbalanced with respect to the nose of the latch to hold the same in engagement with the abutment, a buffer mounted on the inner face of the door in juxtaposition to the lower end of the link to limit its downward movement and also in juxtaposition to the grip of the bell crank lever to limit the movement of the bell crank lever when the latch is tripped, continued pressure upon the grip being transmitted by the buffer to the door.

20 This specification signed and witnessed this 14th day of July, A. D. 1914.

MYRON COSSEY.
